SALIVA EJECTOR

Floyd E. Gibbin, Buffalo, N. Y., assignor of one-half to Leslie A. Gibbin, Springville, N. Y.

Application August 29, 1940, Serial No. 354,690

1. Claim. (Cl. 32—33)

This invention relates to ejectors for removing saliva from the mouth of a patient while undergoing dental work, and is an improvement over the construction shown in Letters Patent of the United States No. 1,471,207.

Saliva ejectors of this type as heretofore made consisted generally of a tube made of spiral strips of paper and a reinforcing wire arranged in said tube so that the latter could be bent into hook shape to fit the mouth of the patient and retain its tubular form.

These prior ejectors possessed objectionable defects due to the fact that the same would become soft and deformed by the flow of saliva through them while in use, also because the end of the same engaging the floor of the mouth was rough, ragged and sharp which caused pain and discomfort to the patient, also because it was possible for the reinforcing wire to project beyond the front end of the tube and injure the patient, also because when shaping the tube to fit the mouth of the patient, cracks were often formed in the tube which caused the same to leak and thus rendered it useless, also because the means for coupling the ejector with the suction apparatus was cumbersome and difficult to handle, and also because these tubes were discolored and unsightly in appearance, due to manufacturing processes formerly used.

It is the object of this invention to provide a saliva ejector which overcomes the above mentioned objectionable features and still permits the same to be manufactured economically.

In the accompanying drawing:

Fig. 1 is a side elevation, on an enlarged scale, of a saliva ejector embodying the improvements of this invention.

Fig. 2 is a longitudinal section, on a still larger scale, of this improved saliva ejector, showing the internal construction of the same.

Fig. 3 is a cross section taken on line 3—3, Fig. 2.

In the following description similar characters of reference indicate like parts in the several figures of the drawing.

As a whole the body of this ejector is generally of tubular form and comprises a straight rear or lower portion 10 which is adapted to be connected with a suction device and a hook shaped front or upper portion 11 which is adapted to be placed in the mouth of a patient for withdrawing saliva therefrom by said suction device while doing dental work thereon.

The main support for the tube of the ejector is provided by an intermediate tubular core of

5 parchment paper which is strong and durable so as to retain whatever shape is given to it. This core is preferably produced by winding two strips 12 of parchment spirally one over the other in a manner well known in the art of making paper tubes. This parchment paper is preferably pure white so as to present a neat and clean appearance and thus avoiding any resistance which otherwise might be offered by patients against placing this ejector in the mouth.

10 To prevent this parchment paper core of the ejector from being softened by the flow of saliva through the same, the inner side of the tubular core is provided with a tubular lining 13 of waterproof paper or similar material which is preferably preformed by winding a strip of this material helically preparatory to placing the strips of core material around the same.

15 Protective means are provided which permit of bending of the tubular core and lining of the ejector so that its upper or front part is of hook shape and still prevent the core and lining portions from becoming cracked or produce 20 leak openings which interfere with the suction of the saliva through the ejector and also permit saliva to escape through these cracks. These protective means consist of an outer coating of cellulose acetate 14 which may be applied to the exterior of the tubular core in any suitable manner but preferably by spraying cellulose acetate in liquid form on the core or winding the same in strip form thereon.

25 Moreover, when bending the ejector tube to form a hook at its upper or front end while this tube is thus coated with cellulose acetate, the inner side of this curved hook portion, as indicated at 15 in Figs. 1 and 2, is comparatively even or smooth and free from protruding or sharp corners or edges, thereby avoiding irritation or discomfort to the patient while holding the ejector in the mouth.

30 This cellulose acetate coating is preferably perfectly clear and transparent so that the white parchment paper is visible through the same and thus emphasizes the impression of cleanliness on the patient and overcomes possible objection to using the ejector in the mouth.

35 Preparatory to bending the tubular ejector body to produce the hook formation on the upper part thereof the same is first heated or warmed moderately which permits of changing the form of the ejector tube without liability of 40 cracking any of its parts and thus reducing the

possibility of producing imperfect ejectors to a minimum.

In the preferred construction the front part of the ejector tube is provided with a crimped or folded flange 16 which is turned backwardly and inwardly against the adjacent part of the bore of the ejector tube, as shown in Fig. 2. By these means a rounded edge 17 is formed on the front end of the ejector tube which upon engaging the floor of the mouth of the patient will not cut the same nor produce any painful irritation such as was manifested when the ejector tube terminated at its front end in a straight transverse cut or edge which left a rough, ragged or sharp surface that is very uncomfortable when held in the mouth of the patient.

In addition to forming a rounded surface on the front end of the ejector tube the inturned flange 16 also forms an internal rearwardly facing shoulder 18 in the ejector tube which is engaged by the front end of the internal reinforcement 9 arranged within the ejector tube. This shoulder therefore forms a stop which is engaged by the front end of the reinforcement and prevents the same from projecting forwardly beyond the ejector tube where it is liable to come in contact with the tissues of the mouth of the patient and produce discomfort and pain. This reinforcement is preferably constructed of a helical piece of wire which extends through the ejector tube throughout the length thereof and is placed in the ejector tube while it is straight and then bent at its upper end into hook form at the same time that the ejector tube is bent into this shape.

Adjacent to its front end the ejector tube is preferably provided in its side with openings 8 through which saliva may pass from the mouth into the tube and thus insure withdrawal of the saliva from the mouth if the front end of the ejector tube should be closed by contact with some part of the mouth. These openings in the front end of the ejector prevent the tissues of the mouth being sucked up into the tube which is highly painful to the patient.

Various means may be employed for connecting the lower or rear end of the ejector tube with the means whereby a suction effect is produced in this tube and saliva is drawn rear-

wardly therethrough from the mouth of the patient. The preferred means for this purpose consists of a sheet metal coupling tube 19 having a cylindrical upper end 20 into which is slipped the lower end of the ejector tube and a downwardly tapering lower end 21 which is slipped into the upper or inlet end of a rubber tube 22 leading to a pump or other suction apparatus whereby a suction is created in the rubber tube. These means for connecting the ejector tube with the rubber suction tube are exceedingly simple and inexpensive and cannot only be handled easily and freely but also are light and neat in appearance as well as permitting the different ejectors to be quickly connected with and disconnected from the suction tube for use with different patients.

By employing an inner layer of waterproof paper, an intermediate layer of white parchment paper and an outer layer of cellulose acetate, a tube is produced which is practically waterproof without requiring any special treatment for this purpose and the original white color of the parchment paper is preserved without any appreciable manufacturing cost.

Moreover, this ejector tube can be very easily adapted to any depth of mouth by curving the hook to fit either a deep or shallow mouth without liability of wrinkling, cracking or injuring the tube and rendering the patient uncomfortable and without spoiling any of the ejectors when effecting such adjustment.

I claim as my invention:

A saliva ejector comprising a tubular body having a curved upper inlet end and a straight lower outlet end, the inlet end of said body being folded backwardly upon itself in the form of a tubular flange from the exterior to the interior of the body and forming an internal inwardly facing shoulder within said body and also forming a rounded edge on the front end of said body, and a helical reinforcing member arranged within the curved and straight ends of said body and engaging its front end with the shoulder formed by the folded flange of said body and thereby preventing said reinforcing member from projecting forwardly beyond the inlet end of said tubular body.

FLOYD E. GIBBIN.
